DESIGN FOR A HAIR CLIPPER

John Oster, Racine, Wis., assignor to John Oster
Manufacturing Company, Racine, Wis., a corporation of Wisconsin

Application December 1, 1941, Serial No. 104,420

Term of patent 14 years

To all whom it may concern:

Be it known that I, John Oster, a citizen of the United States residing at Racine, in the county of Racine and State of Wisconsin, have invented a new, original, and ornamental Design for a Hair Clipper, of which the following is a specification, reference being had to the accompanying drawing, forming part thereof.

The bottom of the clipper is plain.

I claim:

The ornamental design for a hair clipper, as shown and described.

JOHN OSTER.
